UNITED STATES PATENT OFFICE.

I. DE VER WARNER, OF BRIDGEPORT, CONNECTICUT.

MANUFACTURE OF CORSETS.

SPECIFICATION forming part of Letters Patent No. 256,180, dated April 11, 1882.

Application filed January 29, 1881. (Specimens.)

To all whom it may concern:

Be it known that I, I. DE VER WARNER, of Bridgeport, Fairfield county, Connecticut, have invented certain Improvements in the Manufacture of Corsets, of which the following is a specification.

My invention consists in a mode of manufacturing corsets, bosom-pads, &c., whereby to secure a better set and shape, impart greater rigidity and stiffness, reduce the cost of making the articles, and secure greater durability.

Heretofore it has been common in making corsets to make the entire corset of cloth in sections pieced together, forming the pockets in each section, and inserting the bones or ribs separately, either in the pockets before the connection of the sections together or after each connection is made. This mode of manufacture is open to serious objections. Thus the insertion of the ribs or bones is tedious, delays the manufacture, and consequently increases the expense, unless the pockets are made so large that the ribs can be slipped in quickly; but a rib lying loosely in a pocket will not impart such stiffness to the corset as one which is closely confined, and is apt to work in the pocket until the end forms a hole in the cloth, and, further, is liable to break, while the corset is apt to creep up and wrinkle upon the bones and lose its shape. Another objection to the ordinary methods of manufacture arises from the difficulty of pressing, condensing, and finishing an article so irregular in shape as a corset is when all the sections are connected and boned. I overcome these objections in the manner which I will now describe and by the means shown in the drawings, in which—

Figure 1 is a transverse section, showing the manner in which the bones are laid in the sections. Fig. 2 is a view showing the manner of manufacture where continuous rib material is used. Fig. 3 is a longitudinal section through the boned corset-section.

I discard the ordinary method of forming pockets and of inserting the bones or ribs longitudinally, and instead thereof place each bone or rib in position between the two sheets of fabric constituting the front and back portions of the sections or corset, and then sew the two together by a line of stitches as close to the rib or bone as possible. Thus the sheets *b* *c*, Fig.

1, are sewed together along the line *x*, a rib, *a*, is placed between the sheets close to the stitching, and another line of stitches formed at *x* close to the edge of the rib, another rib is placed between the sheets and stitched, and so on until the requisite number is inserted.

Many advantages result from this mode of inserting and securing the ribs. In the first place, no more time is required than usually needed to form the ordinary pockets, thus saving the time, labor, and expense of inserting the bones longitudinally in pockets already formed; secondly, the ribs serve as guides after one is inserted to insure straight lines of stitching with but little care on the part of the operator; thirdly, sheets of fabric are drawn by the stitching close over the bones, so that the latter are held so tight in the pockets that there can be no play and wear, nor can the corset wrinkle up on the ribs, while the rigidity of the article is greatly increased without detracting from its flexibility. Another important advantage of the mode of inserting the ribs results from the ability to use rib material formed in continuous lengths and drawn from a reel and cut off at the extreme edge of each section. Thus a reel, *B*, supplied with a coil of rib material, (as tampico fiber formed into a continuous strip,) is mounted in bearings adjacent to the sewing machine, and the operator, taking the loose end, inserts it between the fabrics of a corset-section, *A*, sews along a line close to the rib, then places another section, *A'*, on the work-plate, and adjusts the rib between the sheets and sews it, and after this is completed does the same with a third section, *A''*, and so on with succeeding sections, as many as may be desirable, and after the rib is secured in the last section, *A''*, cuts it close to the edge at *y*, and carries the loose end to the first section, and repeats the operations again and again until the requisite number of ribs are in each section. The ribs are then cut close to the edges *y'* of each section, thus forming sections in which the ribs are closely confined in the pockets in the act of forming the latter, and in which such ribs extend fully to the edges. The latter fact is one of much importance, as when the binding *b*, Fig. 3, is applied and sewed along the line *e* to the edge of the section the ribs are sewed firmly to the binding

and to the cloth pieces *b c*, the stitches passing through the ribs, so that it is impossible for the ribs to slip or work loose, while their ends bear on the binding, and not on the body cloth, 5 and cannot work through the latter. The curling of the edges of the corset, which results when the ribs extend only a part of the length, is also prevented.

In place of sewing the ribbed sections to 10 the other sections, and thus forming the body of the corset, and then pressing the latter, as is ordinarily done, I press each section while it is flat and before sewing it to the other parts. I thus avoid the difficulties of finishing an irregularly-shaped article, and am enabled to 15 place a number of flat sections upon the flat plate of a press, and at one operation apply such a powerful pressure as will condense and solidify the sections, imparting great stiffness 20 and elasticity, giving a fine finish to the surface, and in the case of the use of tampico ribs or others of like character flattening and consolidating the latter in the pockets and tempering the tampico, if the press-plate is hot. 25 After the sections thus formed are sewed together the corset may be ironed to flatten and finish the seams.

I have found that by the operations above described I am enabled to greatly reduce the 30 cost of making the corset and the length of time required, and make a corset which is

more rigid, more durable, and cheaper than those made in the ordinary way.

I claim—

1. The within-described improvement in the 35 manufacture of corsets, the same consisting in boning the corset by placing the supporting bones or ribs between the outer and inner sheets of fabric, and then sewing the latter together close to the edges of the ribs, thereby 40 securing the ribs in the pockets as the same are made, substantially as set forth.

2. The mode of boning corset sections herein set forth, the same consisting in inserting the end portion of a continuous stiff supporting 45 strip or rib between the outer and inner faces of the section, sewing the same together along the edge of the rib, and then sewing the rib prior to again inserting and sewing it in place, substantially as set forth. 50

3. In the manufacture of corsets the mode of finishing described, consisting in inserting the bones in pockets in the separate sections, pressing the same, and then sewing them into the corset, substantially as set forth. 55

In testimony whereof I have signed my name to this specification in the presence of two subscribing witnesses.

I. DE VER WARNER.

Witnesses:

CHARLES E. FOSTER,
F. O. McCLEARY.

It is hereby certified that in Letters Patent No. 256,180, granted April 11, 1882, to I. De Ver Warner of Bridgeport, Conn., for an improvement in the "Manufacture of Corsets," the word "severing," in line 48, page 2 of the printed specification attached to and forming a part of said Letters Patent, was erroneously printed "sewing;" that the proper corrections have been made in the files and records of the Patent Office, and are hereby made in said Letters Patent.

Signed, countersigned and sealed this 18th day of April, A. D. 1882.

[SEAL.]

A. BELL.

Acting Secretary of the Interior.

Countersigned:

E. M. MARBLE,

Commissioner of Patents.
